United States Patent Office.

HENRY SHUTTS, OF OREGON, MISSOURI.

Letters Patent No. 91,048, dated June 8, 1869.

MECHANICAL MOVEMENT.

The Schedule referred to in these Letters Patent and making part of the same.

To all whom it may concern:

Be it known that I, HENRY SHUTTS, of Oregon, in the county of Holt, and State of Missouri, have invented a new and improved Mechanical Movement; and I do hereby declare that the following is a full, clear, and exact description thereof, which will enable others skilled in the art to make and use the same, reference being had to the accompanying drawings, forming part of this specification.

This invention relates to improvements in mechanical appliances, designed for exerting great force by the application of power with a lever, adapted for operating presses, lifting heavy weights, &c.

It consists in an arrangement of oscillating eccentric-wheel and two sets of cams, the two sets of cams being arranged to act upon the face of the cam-wheel at points opposite to each other, and the cams of each set being arranged to throw in opposite directions, and caused to transmit a reciprocating motion to a sliding bar, all as hereinafter more fully specified.

Figure 1 represents a side elevation of my improved apparatus, and

Figure 2 represents a transverse sectional elevation of the same.

Similar letters of reference indicate corresponding parts.

I arrange, preferably, within a case, A, an eccentric or cam-wheel, B, having four eccentric or cam-facets, *a*, *b*, *c*, and *d*, and a corresponding number of notches, *e*, *f*, *g*, *h*, the facets constituting two sets, at opposite points on the periphery of the said cam-wheel; and the facets of each set are opposed to each other in the direction of their throw.

The aforesaid notches are arranged, one at the root of each eccentric-facet.

C and D represent one set of cams, arranged to operate in conjunction with the facets *a* *b* of the wheel B, and have points adapted to take into the notches *e* *f*, which form the means of keeping the cams in place, the other points, *i* *j*, of the cams being engaged in

notches also, one notch being in the base of the case A, and the other in a ledge in the side of the sliding bar G.

The other set of cams, E F, is similarly arranged, with reference to the opposite face of the cam-wheel, the case A, and the reciprocating bar.

H represents an operating-lever, engaging with the cam-wheel through a slot in the side of the case.

When the lever is moved downward, the cam F will be raised by the rotation of the wheel, and its upper point, taking into the upper notch in the sliding bar, will raise it, while, at the same time, the cam C, whose point *i* rests in the notch in the other end of the sliding bar, will recede, and allow the bar to rise. An upward movement will also be imparted to the wheel by the cam D, whose lower point, being in the notch in the bottom of the case A and the cams C and E, will roll on their respective facets *a* and *c*, being simply, at this time, maintained in their connection with the notches thereby.

If an opposite movement of the operating-lever be made, the cam E will force the wheel downward, and the cam C will give an accelerated downward movement to the slide, while the cams D and F will roll upon their respective facets, being only retained in position, awaiting their time of action, upon the reverse movement of the hand-lever. In this manner, a continuous and powerful reciprocating movement may be imparted to the slide.

Having thus described my invention, I claim as new, and desire to secure by Letters Patent—

The combination of the cam-wheel B, cams C D and E F, slide G, when all combined and arranged substantially as specified.

HENRY SHUTTS.
